DESIGN FOR A LOUNGE

Martin Kaufman, Minneapolis, Minn.

Application May 19, 1947, Serial No. 139,134

Term of patent 14 years

(Cl. D15—11)

To all whom it may concern:

Be it known that I, Martin Kaufman, a citizen of the United States, residing at Minneapolis, county of Hennepin, and State of Minnesota, have invented a new, original, and ornamental Design for a Lounge, of which the following is a specification, reference being had to the accompanying drawing, forming part thereof, and in which

I claim:

The ornamental design for a lounge, substantially as shown.

MARTIN KAUFMAN.
